UNITED STATES PATENT OFFICE.

SERGIUS VERNET, OF BROOKLYN, NEW YORK.

REVERSING MECHANISM.

Application filed March 5, 1924. Serial No. 696,983.

This invention relates to an improvement in reversing mechanism, more especially designed for use in windshield wipers, and other reversing mechanism where compactness and delicacy are prime requisites of the mechanism but capable of use generally in reversing mechanism.

In my copending application Serial No. 641,853, filed May 28, 1923, I have disclosed 10 a windshield wiper operating mechanism in which a warped reversing gear driven by a constantly rotating pinion is mounted so as to slide longitudinally back and forth on the wiper rock shaft to reverse the movements thereof. Due to the enforced smallness of the parts, the necessity for keeping the power consumption at a minimum and the comparatively heavy load on the motor, considerable difficulty has been experienced 15 in securing a uniform rotational drive on the rock shaft near the end of its swing when the pinion is meshing with the warped portion of the reversing gear to shift the gear longitudinally of the shaft, with the 20 result that the effective torque at the ends of the wiper swing may be so greatly reduced that the wiper will sometimes stick at or near the ends of the stroke and stall the motor,—especially if the windshield is 25 gummy or covered with snow or ice. While this difficulty may be overcome by the use of properly designed gear teeth in the warped portion of the reversing gear, it has been found that each tooth in the warped 30 portion must be formed on a different cone and pitch angle and that such extreme accuracy is necessary as to render the production of these gears very difficult.

It is an object of the present invention to 40 overcome this difficulty by providing a means for permitting the shifting of reversing gear back and forth on the rock shaft without causing any substantial rotational movement of the rock shaft, so that the torque at each end of the swing of the wiper or other mechanism carried by the rock shaft will be substantially as great or if desired greater than the torque through the 45 main portion of the swing.

Another object of the invention is to provide a means for permitting reduced rotational drive and increased play between the driving pinion, reversing gear and rock shaft during the longitudinal shifting of the reversing gear on the rock shaft so as to reduce the wear on the guides and other parts

of the mechanism and to reduce the power consumption at this point of the movement.

A more specific object of the invention is to provide a means which will insure a substantially fixed relation between the reversing gear and the rock shaft during the major portion of the swing of the rock shaft, but will permit a slight relative rotation between the rock shaft and the reversing gear 65 near the end of the rock shaft swings when the reversing gear is being shifted longitudinally of the rock shaft.

Various other objects and advantages will appear as the description of the invention 70 proceeds.

Referring now to the drawings which illustrate one form of mechanism by which the invention may be practiced.

Figure 1 is a side elevation of the reversing mechanism in about the middle of its swing.

Figure 2 is a plan view of the same.

Figure 3 is a sectional view approximately 80 on the line 3—3 of Figure 1.

In the form of embodiment illustrated 1 represents the rock shaft, to the end 1^a of which is secured the windshield wiper or other device which it is desired to swing back and forth. A reversing gear illustrated at 2 is mounted on the rock shaft, and comprises the internal bevel gear sectors 3 and 4 connected at each end by integral warped portions 5. A constantly rotating pinion 6 driven by means of a gear or worm 85 wheel 7, preferably dished as illustrated, meshes with the reversing gear 2 to drive the same in all of its positions.

The reversing gear 2 is loosely mounted 90 on the rock shaft 1, and to cause the rock shaft to turn with the gear 2 but permit the gear to shift longitudinally of the shaft, a substantially oval slot 8 is cut in the top of the gear and a pin or screw 9 is fixed to the rock shaft and projects into the slot 8. To 95 reduce friction between the pin 9 and the walls of the slot, a roller 10 may be provided on the pin.

The wheel 7 and pinion 6 are mounted on 100 a fixed stud shaft 11 which extends into the slot 12 formed between the feather 13 and the toothed portions 3, 4 and 5 of the gear 2, and guides the gear 2 in its rotational and longitudinal movement. The wheel 7 may 105 be driven by suitable gearing from an electric motor or any other suitable source of power.

In the operation of the device, starting from the position illustrated in Figure 1, with the pinion 6 rotating in a counter-clockwise direction, the sector 3 and rock shaft 1 is rotated to swing the wiper or other mechanism located on the end 1^a of the rock shaft in a counter-clockwise direction. When the pinion 6 reaches the warped portion 5 at the end of the gear 2 which is shown in Figure 1, the stud shaft 11 is opposite the opening 13^a between the end of the feather 13 and the warped portion 5 so that the gear may be shifted to the right on the rock shaft to put the pinion 6 in mesh with the sector 4 to drive the rock shaft in a clockwise direction until the opposite end of the sector 4 is reached where the gear 2 is again shifted longitudinally on the shaft to reverse the rotation of the shaft.

During the rotational or swinging movements of the shaft 1, the pin 9 and roller 10 occupy a position at one end of the slot 8, so that the gear 2 and the rock shaft swing back and forth in a fixed relation, during the shifting movement of the gear on the shaft, however, the pin 9 and roller 10 move out into the oval portion between the ends of the slot 8, which permits a slight relative rotational movement or play of the gear on the rock shaft, which according to the shape of the slot 8 may be made to reduce or to eliminate entirely the driving of the rock shaft during the longitudinal shifting of the gear thereon. It will, therefore, be apparent that with the reduction or elimination of the drive on the rock shaft during the reversing movement it will no longer be necessary to have such an accurate mesh between the teeth of the pinion 6 and the teeth in the warped portion 5—and that depending on the shape of the slot 8 it may only be necessary to have sufficient contact between the warped portions 5 and the pinion 6 to keep the teeth in mesh during the longitudinal shifting of the gear 2 on the shaft, consequently the necessity for carefully formed teeth in the warped portion 5 no longer exists.

Various modifications may be made in the form of embodiments illustrated without departing from the spirit of the invention or the scope of the appended claims.

I claim:—

1. In a reversing mechanism of the type

described, a rock shaft, a warped reversing gear thereon, means to drive the gear, in alternately reverse direction to oscillate the the rock shaft back and forth, and means to cause a reduction in the driving torque on the rock shaft during the reversing movements.

2. In a reversing mechanism of the type described, a rock shaft, a warped reversing gear, means to drive the gear to swing the rock shaft and to shift it longitudinally of the rock shaft to effect a reversal of the swings, and means to hold the gear fixed on the shaft during the swinging movement and to release the gear for relative rotational movement of the gear on the shaft during the reversing movement.

3. In a reversing mechanism of the type described, a rock shaft, a warped reversing gear on said rock shaft, means to drive the gear, means to cause longitudinal movement of the gear on the rock shaft, means to hold the gear fixed against rotational movement on the rock shaft when in either extreme of its longitudinal movement thereon, and means to release the gear for a slight rotational movement of the gear on the rock shaft during the longitudinal movement of the gear on the rock shaft.

4. In a reversing mechanism of the type described, a rock shaft, a warped reversing gear loosely supported on said rock shaft, an oval opening in the hub of said gear, and a pin on said rock shaft projecting into said opening.

5. In a reversing mechanism of the type described, a rock shaft, a warped internal bevel gear loosely supported on said rock shaft, an oval opening through the hub of said gear, a pin on the rock shaft projecting into the opening and a roller bearing on said pin.

6. In a reversing mechanism of the type described, a rock shaft, a warped reversing gear thereon, means to drive the gear to cause radial movement of the rock shaft, means to shift the gear longitudinally of the rock shaft to reverse said movement, and means to eliminate the radial drive on the rock shaft during the longitudinal shifting of the gear.

In testimony whereof I have affixed my signature to this specification.

SERGIUS VERNET.
